UNITED STATES PATENT OFFICE.

GEORGE VAN WAGENEN, OF NEW YORK, N. Y.

STOVE FOR HEATING CARS, BOATS, &c.

SPECIFICATION forming part of Letters Patent No. 372,832, dated November 8, 1887.

Application filed March 18, 1887. Serial No. 231,382. (No model.)

To all whom it may concern:

Be it known that I, GEORGE VAN WAGENEN, of the city and county of New York, in the State of New York, have invented a new and 5 useful Improvement in Stoves for Heating Railway-Cars, Boats, and for other Purposes, of which the following is a specification.

My invention is more particularly applicable to stoves or heaters which are liable to be 10 overturned or crushed, as are stoves employed in heating railway-cars and boats; and my invention more particularly relates to a stove or heater of the kind which forms the subject of my application for Letters Patent, Serial No. 15 228,015, filed February 18, 1887. The stove which forms the subject of that application is composed of two or more concentric shells or 20 jackets, the fire being within the inner one, and which form a multiple wall containing air-spaces surrounding the fire. I have in that application shown distance pieces or braces which extend between the several shells or jackets and maintain them out of contact with each other, even if the stove be subjected to 25 a blow or force which will crush it.

The object of my present invention is to 30 strengthen the angles or corners which are formed by the several shells or jackets and end plates secured to them, and also to more effectively prevent the transmission of heat outward to the outer shell or jacket, so that the latter can never become red-hot; also, to provide a 35 more certain means for automatically closing the smoke-outlet in case of the stove being overturned.

My invention consists in novel combinations of parts, hereinafter described, and pointed out in the claims, which include angle-braces extending from the corner or angle formed by 40 one shell or jacket, with its end plate, to the corner or angle formed by the next outermost shell or jacket and its end plate, and also include braces or distance-pieces of a novel construction, each of which is usually secured with 45 one end in contact with a shell or jacket and its other end normally out of contact with and in proximity to another shell or jacket.

In the accompanying drawings, Figure 1 is 50 a sectional elevation of a stove or heater embodying my invention. Fig. 2 is a horizontal section thereof upon about the plane indicated

by the dotted line xx , Fig. 1; and Fig. 3 is a similar section on the plane of the dotted line yy , Fig. 1.

Similar letters of reference designate corresponding parts in the several figures.

The fire, which is upon the grate A, is enclosed within a multiple wall comprising air-spaces and formed by two or more concentric shells or jackets, B B' B'', three being here represented. These shells or jackets are closed at the top by end plates, C C' C'', and at the bottom by corresponding end plates, D D' D''. I may make the inner shell or jacket, B, which forms the fire-pot, of cast metal; but the shells 65 or jackets which are external to this are made of boiler-plate or other wrought metal.

E designates the smoke-outlet, which I have shown as coincident in the stove top plates C C' C'' and an aperture in each plate, except 70 the plate C, is protected by a grating, e, as described in my aforesaid application, and the top plates are held at the desired distance apart by braces or flanged distance-pieces E', here shown as rectangular in shape and as 75 bolted or riveted to the top plates C C' C''.

I have here shown a like construction of the several shells or jackets B B' B'', their top plates, C C' C'', and the bottom plates, D D' D'', 80 in so far as the method of joining and bracing them is concerned, and it is obvious that this construction may be employed at either or both ends.

Referring to the top plates C C' C'', it will be observed that the top plates C of the shell 85 or jacket B is connected therewith by bolts c, and that around the upper end of each of the shells or jackets B' B'' is an angle-iron band, b, secured by rivets to the shell or jacket, and that the corresponding top plate C' or C'' is 90 secured in place by bolts b'', which extend through the top plate and through the horizontal flange of the angle-iron b.

I have shown braces or distance-pieces F as secured between the shells or jackets B B' B'', 95 as I shall soon describe, or between the top plates, C C' C''; but in so far as described no means are provided for bracing the angles formed between the top plates and their respective shells or jackets B B' B''. To brace 100 the structure at these points, I provide angle-braces G G'. These angle-braces may be formed

of cast-iron or malleable iron, and are arranged in circular series at suitable distances around the circumference of the stove, as is best shown in Fig. 2. Each of them may be formed with a rabbet, d , fitting an inner shell or jacket, and its top plate or end plate, B C , for example, and at its outer end the angle-braces may fit against the next outermost shell or jacket and top plate, B' C' , for example. I have represented the braces G G' as secured in position by the same bolts, c b^2 , which hold the top plates C C' on their respective shells or jackets B B' ; and it will be observed that these braces sustain the shells or jackets at the corners or angles which are formed by the joining of the end plates C C' to them, and thus brace what otherwise might be considered the weak point in the structure.

The braces F , which I have shown as arranged between the shells or jackets B B' , and also between the end plates, C C' C^2 and D D' D^2 , may be made of cast or malleable or other metal, and, as represented, they have broad ends which give them an extensive bearing against the parts which they separate, and prevent them from upsetting or turning over in case of a crushing force or blow being delivered upon the stove at any point. I have shown each brace F as secured by a rivet, f , to the shell or jacket, or to an end plate, and it may be recessed in its end, as at f' , to receive the head of the rivet f . The braces F are each secured with one end against a shell or jacket or end plate and with its other end normally out of contact with but in close proximity to the adjacent shell or jacket or plate. The narrow spaces f^2 thus afforded between the end of the brace F and the shell or jacket adjacent to that to which it is secured prevents the rapid conduction of heat to the outer shell or jacket, and will prevent the same from becoming red hot. Notwithstanding these spaces f^2 , a blow or crushing force exerted upon the stove will bring the braces or distance-pieces F to a bearing on the shell, jacket, or plate toward which they extend, and they will prevent the shells, jackets, or plates from being forced into contact with one another, and will therefore prevent the exterior of the stove from ever becoming red-hot, so that it would set fire to surrounding objects.

In order to still further guard against the outer jack or shell, B^2 , ever becoming red-hot, I have represented a washer, f^3 , of non-conducting material—such as asbestos—introduced between the outer shell or jacket, B^2 , and between the end plates C^2 D^2 and the braces or distance-pieces F , secured to them.

It will be observed that at the bottom of the stove I have shown the same construction of angle-braces G G' as at the top, and the same letters of reference apply to the construction of the joints between the shells or jackets B B' B^2 and the bottom plates, D D' D^2 .

The smoke-outlet E in the plate C is not protected by any grating, but constitutes a valve-seat, against which a ball or spherical

valve, H , closes by gravity in case of the stove being overturned. I have here represented the valve H as supported by arms or knees 70 H' , extending radially inward from the shell or jacket B , which constitutes the stove-body, and held at proper relative distances apart by a ring or annular brace, H^2 . Any crushing action from collision or otherwise exerted 75 upon the stove-body while upright will raise the inner ends of the arms H' at their points of contact with the ball or sphere H and lift the ball to its seat in the smoke-outlet before the stove is overturned, thus preventing any 80 unforeseen obstacle from interfering with its closing by gravity. The inner shell or jacket, B , may be made of wrought-iron down to the joint b^3 , formed by bolts or otherwise, with the fire-pot B^3 , which latter may be of cast metal. 85 The stove may have suitable doors, which may be held by fastenings, such as those shown in my applications for Letters Patent, Serial Nos. 228,015 and 228,692, filed, respectively, February 18 and 24, 1887. 90

I do not claim herein a brace or distance piece, F , broadened at one end only, as my application No. 230,153, filed March 4, 1887, shows such a brace riveted to the shell or jacket at one end and broadened at its free end; 95 but I only seek to cover herein such a brace broadened both at its free end and at the end where it is secured to the shell or jacket.

I am aware that it is not broadly new to provide within a stove-body a ball, which, when the stove is overturned, will roll into position to close the smoke-outlet and absolutely prevent the escape of coals. In case of railroad accidents, however, the stove in most cases is liable to be crushed before being overturned, and if it be crushed, ordinarily such a ball would be jammed in its inoperative position and could not roll to close the smoke-outlet when the stove is accidentally overturned. I therefore combine with a ball for closing the smoke-outlet a series of arms—such as H' —which extend inward from the side walls of the stove, and which have a point of attachment with the wall of the stove at about the bottom of the ball, and when the ball is thus 115 supported and the stove is subjected to a crushing action or bent inward its sides will throw up the arms H' , and will thus lift the ball to the position to close the smoke-outlet before the stove is ever overturned. This result cannot be secured by arms or fingers depending from the top of the stove or from a point above the ball and serving to sustain the ball, and the result can only be secured by arms—such as H' —which have a point of attachment to the stove-wall about on a level with the bottom of the ball. 120

What I claim as my invention, and desire to secure by Letters Patent, is—

1. The combination, in a stove, with multiple walls separated by air-spaces and composed of cylindric shells or jackets and end plates secured to the cylindric shells or jackets, of one or more angle-braces extending from

the corner or angle formed by one shell or jacket and its end plate to the corner or angle formed by the next outermost shell or jacket and its end plate, substantially as herein described.

2. The combination, in a stove, with multiple walls separated by air-spaces and composed of cylindric shells or jackets and end plates secured to them, of one or more circular series of angle braces or knees, G G', extending from the corner or angle formed by one shell or jacket and its end plate to the corner or angle formed by the next outermost shell or jacket and its end plate, substantially as herein described.

3. The combination, with the two or more concentric shells or jackets and their end plates, of the angle-iron band b at the joint between each shell or jacket and its end plate and the circular series of angle braces or knees G G', substantially as herein described.

4. The combination, with two or more concentric shells or jackets and their end plates, of braces or distance-pieces secured with one end in contact with a shell or jacket and its other end normally out of contact with but in proximity to the adjacent shell or jacket, substantially as herein described.

5. The combination, with two or more concentric shells or jackets and their end plates, of braces or distance-pieces F, each secured to

a shell or jacket at one end, and having both its free end and the end which is secured to the shell or jacket broadened to give an extensive bearing on the two shells or jackets 35 between which it is placed, substantially as herein described.

6. The combination, with two or more shells or jackets and end plates, of the braces or distance-pieces F, each secured by a rivet, f, to one shell or jacket and recessed at the end to receive the head of the rivet, and adapted to preserve approximately the distance between the two shells or jackets, substantially as herein described.

7. The combination, with a stove having at the top a smoke-outlet, E, of the ball-valve H, for closing the same in case of the stove being overturned, and a series of radial arms, H', extending inward from the side wall of the 50 stove, and having a point of connection with the stove-wall about opposite the bottom of the ball, whereby the arms will serve to support the ball-valve and to raise it to close the outlet in case the stove is crushed in before 55 being overturned, substantially as herein described.
